UNITED STATES PATENT OFFICE.

EDWARD L. GUSTAFSON, OF HOLDREGE, NEBRASKA.

RACK FOR POOL BALLS.

Application filed June 13, 1925. Serial No. 36,979.

To all whom it may concern:

Be it known that I, EDWARD L. GUSTAFSON, a citizen of the United States, residing at Holdrege, in the county of Phelps and State of Nebraska, have invented certain new and useful Improvements in Racks for Pool Balls, of which the following is a specification.

This invention relates to racks for holding the balls used on pool tables after they have been removed from the pockets, and for retaining them until the retaining or delivery slide of the rack is released by the insertion of a coin of predetermined value; and it consists in the novel construction and combination of the parts hereinafter fully described and claimed.

In the drawings, Figure 1 is a side view of a rack constructed according to this invention. Fig. 2 is a rear end view of the same showing the delivery slide. Fig. 3 is a side view of the coin-controlled mechanism with the cover removed. Fig. 4 is a longitudinal section through the rack, taken on the line 4—4 in Fig. 2. Fig. 5 is a front end view of one of the entrance chambers, showing the hole through which the balls are inserted. Fig. 6 is a sectional plan view, taken on the line 6—6 in Fig. 1. Fig. 7 is a sectional plan view, taken on the line 7—7 in Fig. 1. Fig. 8 is a sectional plan view, taken on the line 8—8 in Fig. 3.

Two similar ball chambers 10 and 12 are provided, and are arranged one above the other. These two chambers are both alike, and they are arranged at a slight inclination from the horizontal, so that the balls will run along them. Each chamber has a slot 14 in one side so that the balls can be seen inside it. Each chamber has a similar entrance chamber 15 at the top of its higher end, and each entrance chamber has an entrance hole 16 at its front end and out of line with the ball chamber. Each entrance hole is made of a diameter that will just permit a ball to be entered through it, and the ball when inserted drops through the entrance chamber and rolls down the inclined ball chamber pertaining to it.

The object of the entrance chamber is to trap the balls, and prevent their removal from the machine except at its rear end, and after the insertion of a coin. The rear end portions of the two-ball chambers 10 and 12, are provided with a single delivery slide 17

having a delivery opening 18. The two ball chambers are secured to uprights or bars 19, and these bars afford a means for securing the machine to a pool table, or to any other suitable support, such as the wall of a pool room. The slide 17 is slideable vertically in guides 20 at the rear end of the machine, and when raised by hand the balls in the upper ball chamber 10 roll out of it through the opening 18, and the balls in the lower ball chamber 12 roll out of it below the bottom edge of the slide.

The coin-operated mechanism is arranged between a plate 24 secured to the ball chambers, adjacent to the slide, and a removable cover plate 25 secured parallel to the plate 24. A block 26 is secured between the plates 24 and 25, and is provided with a vertical guide channel 27 in which a coin bar 28 is slideable. The lower part or extension 29 of the channel 27 forms the coin delivery chute. The cover plate 25 has a hole 30 in its lower part for the insertion of a coin, and it has a vertical slot 31 above the hole 30. An operating pin or handle 32 is secured to the coin bar 28, and projects through the slot 31, and affords a means for sliding the coin bar up and down by hand. A stop plate 34 is arranged to slide horizontally in a guide 35 at the top of the coin chute 29, and this plate 34 has a projection 36 which is slideable in one end portion of the guide 35 and in a rectangular guide notch 37 in the block 26.

A spring 38 is arranged in the notch 37, and normally holds the projection in the path of the coin bar, as shown in Fig. 1, and prevents it from being pushed downwardly to its full extent. When, however, a coin is inserted through the hole 30, as indicated in dotted lines in Fig. 3, and the coin is pushed down, the coin retracts the stop plate 34, and is discharged down the chute 29, and permits the lower end of the coin bar to pass the stop plate. A closed bank or coin receptacle 41 is arranged under the coin chute 27, and has a hinged door 42 provided with any suitable lock 43.

The slide 17 has a projecting lug 44 which projects between the plate 24 and the cover plate 25, and 45 is a pawl pivoted on a pin 46 between the said plates. This pawl is pressed rearwardly at its lower end by a spring 47 so that it projects above the lug 44, and prevents the slide from being raised

from its lowered position in which it closes the delivery ends of the ball chambers. A projection 48 is formed on the upper end portion of the coin bar 28, and when the 5 coin bar is pushed down past the stop plate 34, this projection 48 engages with the upper end portion 49 of the pawl, and retracts its lower end so to permit the slide 17 to be raised by hand.

- 10 The slide 17 has an arm 50 secured to it, and when the slide is raised this arm comes in contact with a projection 51 on the coin bar, which projection may be an extension of the pin 32, so that the coin bar is raised 15 automatically, and is restored to its normal position above the coin hole 30, and out of engagement with the pawl.

A toothed rack 54 is secured to the slide 17, and a double-acting pawl 55 is pivoted 20 by a pin 56 to the supporting bar 19 adjacent to the slide, and is adapted to engage with the teeth of the rack. A spring 57 holds the pawl 55 in a horizontal position and clear of the teeth of the rack at the 25 ends of the stroke of the slide. When the slide is raised or lowered the teeth tilt the pawl on its pivot, and the pawl then prevents the return movement of the slide until it has made a full stroke, and the pawl has 30 resumed its horizontal position. This insures a satisfactory working of the coin-controlled mechanism.

A separate machine is provided for each 35 pair of players. The balls which drop into the pockets of the pool table are placed by the party playing them in one of the ball chambers, and the other party places his balls in the other ball chamber after removing them from the pockets. When all 40 the balls have been played, the balls are counted, and the losing party puts a coin into the machine and pushes it into the bank, so that all the balls can be released. The game is resumed, and when finally finished 45 the proprietor of the pool table removes the coins from the bank.

When a pool room is provided with a machine of this sort the proprietor does not have to be on hand to collect separate coins 50 at short intervals, but can get all his money at one time after the players have finished, and can then see that all the balls are ready for other players.

What I claim is:

55 1. In a rack for pool balls, a ball chamber having an opening in one end portion of its top, and an entrance chamber for the balls arranged over the said opening and provided with an entrance opening in one 60 of its vertical sides.

2. In a rack for pool balls, a pair of ball chambers arranged one above the other, each ball chamber having an opening at one end, entrance chambers communicating with the 65 said openings and provided with entrance

openings which are out of line with the ball chambers to which they pertain, and a single delivery slide for the balls arranged at the other ends of the ball chambers and common to both.

70 3. In a rack for pool balls, a ball chamber, a ball delivery slide normally closing one end of the ball chamber, a pivoted pawl normally preventing the opening movement of the said slide, a block provided with a guide channel having a coin opening in one side, a coin push-bar slideable in the upper part of the guide channel and provided with means for retracting the said pawl, and a retractable stop for the push-bar arranged crosswise of the guide channel below the coin opening, the said push-bar operating positively to retract the pawl after retracting its stop by means of a coin.

75 4. In a rack for pool balls, a combination of parts as set forth in claim 3, the said coin delivery slide being also provided with means for raising the coin push-bar to its normal position when raised to open the ball chamber.

80 5. In a rack for pool balls, a ball chamber, a slide normally closing the delivery end of the ball chamber and provided with a projection, a pivoted pawl normally engaging with the said projection and preventing the opening movement of the slide, coin-controlled devices provided with means for retracting the said pawl to release the slide, and means carried by the said slide and operating to 85 release the pawl automatically, when the slide has been operated to release the balls.

6. In a rack for pool balls, a ball chamber, a slide normally closing the delivery end of the ball chamber and provided with a projection, a pivoted pawl normally engaging with the said projection and preventing the opening movement of the slide, coin-controlled devices provided with means for retracting the said pawl to release the slide, and means which constrain the said slide to 100 make a full stroke in each direction before moving in the reverse direction.

7. In a rack for pool balls, a ball chamber, a slide normally closing the delivery end of the ball chamber and provided with a projection, a pivoted pawl normally engaging with the said projection and preventing the opening movement of the slide, coin-controlled devices provided with means for retracting the said pawl to release the slide, a toothed rack secured to the said slide, and a pivoted double-acting pawl adapted to engage with the toothed rack and constrain the slide to make a full stroke in each direction before moving in the reverse direction.

8. A rack for pool balls, comprising two ball chambers arranged one above the other and provided at one end with entrance chambers arranged out of line with the ball cham-

bers, a single delivery slide arranged vertically at the outlet ends of the ball chambers and common to both, a closed coin receptacle secured under the delivery end portion of the lower ball chamber, and coin-controlled mechanism arranged at one side of the delivery end portions of the ball chambers above the coin receptacle and provided with

a coin chute communicating with the coin receptacle, said coin-controlled mechanism operating normally to prevent the opening movement of the delivery slide. ¹⁰

In testimony whereof I have affixed my signature.

EDWARD L. GUSTAFSON.
